MUFFLING DEVICE

Francis A. Jimerson, Athens, Pa., assignor to
Ingersoll-Rand Company, Jersey City, N. J., a
corporation of New Jersey

Application October 4, 1934, Serial No. 746,778

1 Claim. (Cl. 181—42)

This invention relates to muffling devices, and more particularly to an exhaust muffling device for fluid actuated motors.

One object of the invention is to effectively suppress the sound waves induced by the emission of the fluid from the motor and to transform the exhaust impulses into a substantially steady stream.

Another object is to provide a simplified and effective structure which will not add materially to the weight of the motor to which it is appended and which may be readily and cheaply replaced.

Other objects will be in part obvious and in part pointed out hereinafter.

In the drawing accompanying this specification and in which similar reference numerals refer to similar parts,

Figure 1 is a sectional elevation of a muffling device constructed in accordance with the practice of the invention and showing it applied to a fluid actuated rotary motor, the latter being partly broken away, and

Figure 2 is a transverse view taken through Figure 1 on the line 2—2.

Referring more particularly to the drawing, the muffling device designated, in general, by 20 is shown applied to a fluid actuated rotary tool 21 comprising a cylinder 22 and front and back heads 23 and 24 which may be secured to the cylinder in any suitable manner.

The cylinder 22 has a bore 25 to accommodate a liner 26 the interior of which constitutes a piston chamber 27 containing a rotor 28 having shaft portions 29 which extend into anti-friction bearings 30 in the cylinder and the back head. The rotor has a plurality of radial slots 31 in which are disposed vanes 32, and in one side of the liner are a series of inlet ports 33 which communicate with a supply passage 34 to admit pressure fluid into the chamber 27 for operating the rotor 28. The exhaust fluid passes from the chamber 27 through a series of exhaust ports 35 in the liner 26 and through a recess 36, defined by the liner and the bore 25, to an exhaust port 37 in the wall of the cylinder 22.

The muffling device 20 is arranged on the exterior of the cylinder 22 adjacent the exhaust port 37. It is encased by a hollow extension 38 which may be an integral part of the cylinder and the interior of which constitutes an exhaust chamber 39. Overlying the outer end of the chamber 39 is a plate 40 which seats against the extension 38 and is secured in position by a bolt

41 extending through the muffling device and threaded into a boss 18 on the outer surface of the cylinder 22. The plate 40 is of less width than the open end of the chamber 39 to define an exhaust port 45 through which the fluid issuing from the sheet 42 may pass to the atmosphere.

In the form of the invention illustrated, the muffling device 20 consists of a sheet 42 of permeable material, as for example, felt. The sheet is preferably folded to U-shape of which the curved portion lies adjacent the wall of the cylinder and the legs lie on opposite sides of the bolt 41 and seat upon the plate 40. The sheet extends from one side wall to the other of the chamber 39 and its upper edge seats against the boss and combines therewith and with the wall of the cylinder to define openings 19 on opposite sides of the boss for the passage of the major portion of the exhaust fluid from the port 37 to the port 45.

A suitable container is provided for the sheet 20 42 in the form of a U-shaped plate 43 of which the curved portion and the legs lie exteriorly of the corresponding portions of the sheet. The container is preferably of the same length and 25 height as the sheet 42 and has a series of perforations 44 through which exhaust fluid may pass into and from the sheet 42.

In practice the present invention has been found to be a highly efficient device for suppressing the sound vibrations caused by the intermittent impulses of the exhaust fluid issuing from the motor. Upon entering the chamber 39 the exhaust fluid is expanded and in passing through the chamber the impulses are evened out without 35 causing any appreciable back pressure. The exhaust fluid, therefore, finally passes through the exhaust port 45 as a substantially constant stream.

I claim:—

A muffler comprising a casing having an expansion chamber, said casing having an inlet opening and an outlet opening, a cover plate for one end of the casing and cooperating with the casing to define the outlet opening, a wall of permeable material extending from one side wall to the other of the casing between the openings and cooperating with the top of the casing to define a passageway from the inlet opening to the outlet opening, and a bolt extending through the cover plate and the wall and being threaded into the casing to secure the cover plate and the wall rigidly to the casing.

FRANCIS A. JIMERSON. 55
